UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

STITCH-FORMING MECHANISM FOR SEWING MACHINES.

Application filed February 18, 1922. Serial No. 537,382.

To all whom it may concern:

Be it known that I, EDWARD B. ALLEN, a citizen of the United States, residing at Newtown, in the county of Fairfield and State 5 of Connecticut, have invented certain new and useful Improvements in Stitch-Forming Mechanisms for Sewing Machines, of which the following is a specification, reference being had therein to the accompanying 10 drawings.

This invention relates to overseaming stitch-forming mechanism more particularly of the type disclosed in the patent to Allen et al., No. 1,372,473, March 22, 1921, 15 and adapted for buttonhole sewing. The invention has for an object to provide the stitch-forming mechanism with means facilitating the setting of the purl close to the edge of the seam or, when sewing button- 20 holes, close to the buttonhole slit.

In stitch-forming mechanism of the character under consideration, the concatenation of the looper-thread with the needle-loops forms the purl and, in accordance with the 25 present improvement, a device is interposed between the looper and the work for holding the looper-thread leading from the looper to the last stitch in an elevated or more nearly horizontal position than heretofore, so that when the looper is retracted to 30 tighten the looper-loop, such loop will be set over close to the buttonhole-slit without straining or distending the previous needle-loop. The purl or line of the interlocked 35 needle and looper-thread loops will thus be set over close to the buttonhole-slit.

In the accompanying drawings, Fig. 1 is a front elevation of stitch-forming devices embodying the present improvement. Fig. 2 40 is a left side elevation of the same. Fig. 3 is a right side elevation of one of the loop-detaining elements shown in Figs. 1 and 2 and Fig. 4 is a fragmentary view similar to Fig. 2 but at a later stage in the stitch-forming cycle.

In the specific embodiment of the invention chosen for the purposes of the present disclosure 1 represents the reciprocating and laterally jogging needle of the well known 45 type disclosed in said Allen et al. patent. The needle 1 is so actuated as to pass alternately through the buttonhole-slit 2 in the work 3 and at a distance from such slit. The work 3 is held clamped by the lower work-

supporting plates 4 and upper clamping 55 feet 5 of a suitable machine such as that disclosed in my Patent No. 1,372,472, of March 22, 1921.

Cooperating with the needle 1 are the lower looping devices which are mounted on the usual turret 6 and comprise the threaded-looper 7, non-threaded looper 8, and loop-detainers 9 and 10. The loopers 7 and 8 are carried by the arms 11 and 12 of a rocking looper-carrier which is pivoted at 13 to the 60 post 14 rising from the turret 6. The loop-detainers oscillate alternately about their common pivotal support 15; the actuating mechanism being the same as heretofore. The turret carries the usual needle-throat or 65 button 16.

Referring to Fig. 1 it will be observed that the needle 1 is rising from its depth-stitch descent; its loop 17 having been seized and carried to the left by the non-threaded 70 looper 8 into position for seizure by the horn 18 of the loop-detainer 9; the latter having in the meantime been advanced from dotted line position, Fig. 2, to full line or 75 loop-seizing position. The looper-thread 19 leads downwardly from the work to the threaded looper 7 and, during the retraction of the looper 7 to the position shown in Fig. 1, a pull is exerted on the looper-thread. Heretofore this pull was exerted in a direction 80 from the last stitch straight to the eye of the threaded looper, and such direction was inclined at an angle of 45° or more to the plane of the work, making it difficult to 85 set up the concatenated loops without disturbing or distending the loops previously 90 set up.

In accordance with the present improvement provision is made for supporting the looper-thread between the looper and the work, so that the looper-thread length adjacent the last stitch will extend away from the buttonhole-slit in a more nearly horizontal direction than heretofore, whereby the pull on the looper-thread will have a 100 large lateral component and an insignificant vertical component. By so supporting the looper-thread, the purl may be effectively pulled over to the buttonhole-slit and a buttonhole of satisfactory appearance produced even though the looper oscillates about a horizontal axis as is customary in turret 105 machines.

The means for supporting the looper-thread may conveniently be made up in the form of a horn 20 rigid with or secured to the loop-detainer 9 and having a down-turned point 21 projecting forwardly beyond and over the horn 18, so as to pass below the looper-thread 19 and lift the latter toward the work 3. The horn 20 also serves to separate the looper-thread from the 10 needle-loop 17 and hold the looper-thread 19 clear of the horn 18 so that as the horn 18 advances to seize the needle-loop 17 it will not catch the looper-thread. On the slit-stitch descent of the needle, Fig. 4, it 15 passes in front of the looper-thread 19 and into the needle-loop 17 which is held spread by the horn 18 of the loop-detainer 9.

The invention is not to be understood as limited to the form and arrangement of parts 20 shown and described as it is believed to be broadly new to provide means cooperating with the threaded-looper of an overseaming stitch-forming mechanism to bend the looper-thread between the looper and the last 25 stitch and thereby facilitate the setting of the purl close to the edge of the work.

Having thus set forth the nature of the invention, what I claim herein is:—

1. In overseaming stitch-forming mechanism, the combination with needle and looper devices for concatenating needle and looper threads to form a purl stitch, of means for bending toward the plane of the work the length of looper-thread between the 35 looper and the last stitch, thereby facilitating the setting of the purl close to the edge of the seam.

2. In overseaming stitch-forming mechanism, the combination with needle mechanism and looper mechanism including threaded and non-threaded loopers operating alternately about substantially horizontal 40 axes to seize needle-loops, of means for bending the length of looper-thread between the 45 threaded looper and the last stitch toward the plane of the work while the non-thread-

ed looper is in engagement with a needle-loop, substantially as and for the purposes specified.

3. Overseaming stitch-forming mechanism comprising, needle mechanism operating to pass depth-stitch and slit-stitch needle-loops alternately through the work, threaded and non-threaded loopers operating alternately to seize such loops, and a 50 loop-detainer having a horn for seizing the depth-stitch needle-loop on the non-threaded looper, said detainer having a second horn disposed above said first mentioned horn and adapted to separate the looper-thread from the depth-stitch needle-loop.

4. Overseaming stitch-forming mechanism comprising, needle mechanism operating to pass depth-stitch and slit-stitch needle-loops alternately through the work, threaded and non-threaded loopers operating alternately to seize such loops, and a 55 loop-detainer having a horn for seizing the depth-stitch needle-loop on the non-threaded looper, said detainer having a second horn disposed above and projecting forwardly of said first mentioned horn and adapted to separate the looper-thread from the depth-stitch needle-loop.

5. Overseaming stitch-forming mechanism comprising, needle-mechanism operating to pass depth- and slit-stitch needle-loops alternately through the work in different paths, a threaded looper for seizing the slit-stitch needle-loop, a non-threaded 60 looper for seizing the depth-stitch needle-loop, and a pair of loop-detainers for seizing the loops from their respective loopers and positioning them unassisted by said loopers for entry by the needle, the loop-detainer 65 which cooperates with the non-threaded looper being formed with a loop-seizing horn and with a looper-thread deflecting horn overhanging the loop-seizing horn.

In testimony whereof, I have signed my 70 name to this specification.

EDWARD B. ALLEN.
